UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

TRAVELING-CYLINDER WEB-PRINTING PRESS.

No. 880,001..

Specification of Letters Patent.

Patented Feb. 25, 1908.

Application filed April 22, 1907. Serial No. 369,550.

To all whom it may concern:

Be it known that I, HENRY F. BECHMAN, of Battle Creek, in the county of Calhoun and State of Michigan, have invented certain new and useful Improvements in Traveling-Cylinder Web-Printing Presses; and I hereby declare that the following is a full, clear, and exact description thereof, reference being had to the accompanying drawings, which form part of this specification.

This invention is an improvement in traveling cylinder web printing presses of the well-known "duplex" type, although applicable to other kinds of presses. Its object is to enable two webs to be fed through the printing mechanisms at different speeds, so that both webs may be printed from different forms by the same printing couples, different lengths of each web being printed at each operation of the press, and each web being fed through the press at a predetermined speed and thereafter the products of the two webs can be assembled together. As applied to presses of the duplex type, for example, if the cylinders have a travel sufficient to cover two forms arranged one after the other upon the bed, impressions can be taken from both forms on one web and impression can be taken on the other web from a single form placed on the same bed. Thus eight or twelve pages could be printed simultaneously on one web by using a double set of forms on each bed, and at the same time two pages could be printed upon the narrow web by the same beds and cylinders from single page forms placed on the beds. This would necessitate feeding the wide web through the press at about twice the speed of the narrow web, and for this reason I have provided means whereby the webs can be fed and delivered at the necessary speed, and whereby each web may be properly looped according to the rapidity of its feed. In carrying out this feature of the invention I preferably make the web-feeding and delivering cylinders in two sections and provide gearing whereby the shorter sections of the cylinders which handle the narrow webs can be run at lower speed than the longer sections thereof which handle the wide web, so that the narrow web can be fed at the desired slow speed relative to the wide web. I also provide novel looping mechanisms whereby each web will be looped at the proper times, in accordance with its rate of

feed and delivery, the narrow web for example being looped only half as fast and to half the extent of the wide web; and preferably both said looping mechanisms are controlled by a single cam in this invention. 60

By lengthening the throw or travel of the cylinders of an ordinary 8-page duplex press I am enabled to print 2, 4, 6, 8, 12 or 16 pages thereon on a single web, using a full width web and double set of forms on each bed when printing 16 pages, and a narrower web and double arrangement of forms when printing 8 or 12 pages; and when it is desired to print 10 or 14 pages I use a wide web and double set of forms to print 8 or 12 pages, 70 and a second narrow web and single forms on each bed, and assemble the resultant product of the narrow web with the product of the wider web of the folder.

I will now describe the invention with 75 reference to the machine illustrated in the accompanying drawing, in which—

Figure 1 represents diagrammatically a duplex press equipped with my novel feeding and delivering mechanisms, whereby 80 two webs may be fed through the press at different speeds. Fig. 2 is a detail sectional view illustrating the construction and mode of gearing the sectional feeding and delivering cylinders, whereby two webs may be fed 85 through the press at different speeds. Fig. 3 is a detail view of the web looping devices. Figs. 4 and 5 are detail views illustrating the arrangement of forms for printing a ten-page and fourteen-page paper. 90

In the drawings 1 and 2 are type beds adapted to carry two rows of type forms, as indicated in Figs. 4 and 5. 1^a and 2^a are the cylinders, co-acting with the forms on said beds, which may be mounted in sliding 95 carriers 3 and reciprocated back and forth of the bed by means of connecting rods 3^a operated by crank wheels 3^b, as in the "duplex" press. The beds and cylinders are preferably arranged as in the ordinary 100 duplex press and require no detailed description herein as the construction is well understood.

The feeding-in devices 4 and delivery devices 5 are arranged substantially as in the 105 duplex press, and the guides and looping devices for handling the main web are arranged substantially as in the duplex press and need no detailed description; but will be readily understood by following the 110

course of what I shall term herein the "wide web" indicated at W in the drawings. This web W is led in under a guide 2^x and between the lead rolls 4 down under 5 the guide 6^a, up over looping roller 6^b, down under a guide 6^c to and over a guide 6^e, then between bed 1 and cylinder 1^a, up over guide 6^a, back to, under and over guides 6^h, 6ⁱ, back over guide 6^j between cylinder 2^a and 10 bed 2; thence over guide 6^k to guide 6^l, then down under looping roller 6^m, then up over guide 6ⁿ to the delivery rolls 5. The guides 6^e, 6^f, 6^j, 6^k, are mounted on the cylinder carriers and travel with the cylinders. The 15 looping rollers 6^b and 6^m are mounted in a reciprocating frame 8, which is operated by means of a link 8^a connected to a lever 8^b, which is vibrated by means of cam 8^c, as in the duplex press; the parts being operated 20 in such manner that during the taking of an impression, while the cylinders 1^a, 2^a, are rolling over the type forms, the web fed in by the feeding rollers is taken up by the ascent of looping roller 6^b, while a like 25 amount of web is given out by the ascent of the looping roller 6^m, so that the in-feed and out-feed of the web is continuous, as in the duplex press, and between impressions the looping rollers are lowered so that the loop 30 of web formed over 6^b is transferred to the looping roller 6^m and enough of the web is shifted forward between the beds and cylinders to bring unprinted portions of the web into position to be printed at the next 35 movement of the cylinders over the form.

The web w, which I will call the "slow web", is guided similarly through the press but is operated at say half the speed of web W. In order to feed and deliver this web w at 40 half speed I preferably make the feed and delivery rollers 4 and 5 in sections, as indicated in Fig. 2; the fast section 4^a of roll 4 is fixed to the shaft 4^b which is driven by a suitable train of gears 4^c from the drive shaft 45 at the proper speed to feed the web W into the press at the desired speed.

The slow section 4^e of the feed roll 4 is rotatably mounted on shaft 4^b and is driven, at say half the speed of section 4^a, by means of 50 the pinion 4^f on section 4^e meshing with a pinion 4^g on the stub shaft 4^h journaled in the frame and carrying a gear 4ⁱ meshing with a gear 4^j keyed on the shaft 4^b, so that the slow section 4^e is driven from shaft 4^b at 55 a much slower rate than section 4^a. The delivery roll 5 is similarly constructed with fast and slow sections 5^a, 5^e, which are driven at the same speed as the sections 4^a, 4^e, of the in-feed roll, by means of trains of gears 60 4^d and 4ⁿ, as indicated in Fig. 2 of the drawing.

By properly proportioning or varying the diameters of gears 4^j, 4ⁱ, any desired difference between the peripheral speeds of sections 4^a, 4^e, can be obtained; and where a

full width web is to be printed, the sections may be driven at the same speed by substituting suitably proportioned gears for the gears 4ⁱ, 4^j.

Assuming that two webs are to be printed, 70 and that the slow sections 4^e, 5^e, are geared at half the speed of the fast sections 4^a, 5^a, so as to feed the narrow slow web w one-half as fast as the wide fast web W, it is necessary to provide means for looping the web w in 75 accordance with its slower in-feed and delivery. A very simple and effective way of looping this web is indicated in the drawings. As shown, the web w passes from a roll under suitable guides over the slow in-feed section 80 4^e, and thence under a fixed guide 7^a over a looping roller 7^b, down under guide 7^c, and thence over the guide 6^e beside and along with the wide web W between the beds and cylinders and as far as guide 6^k; then the 85 narrow web w passes over a guide 7^d, down under a looping roller 7^m, up over a guide 7ⁿ to the slow feed section 5^e of the delivery mechanism. The looping rollers 7^b and 7^m are mounted in a frame 9, which is pivotally 90 connected at 9^d to a lever 9^a, which is pivoted at 9^b to a fixed point of the frame and its forward free end is pivoted to the frame 8, as shown. The pivot 9^d is midway between the pivots 9^b and 9^c and therefore the frame 9 95 will be moved by and with the frame 8 but will only move half the distance traveled by frame 8, consequently the looping rollers 7^b, 7^m will only move half the distance of the looping rollers 6^b, 6^m, and at half the speed of 100 the latter, and thus the web w will be looped exactly in accordance with its feed and delivery, and the one set of looping cams 8^c will care for both sets of loopers.

From the foregoing it will be obvious that 105 each web will be fed through the press and looped and delivered at the desired speed and in the desired time, and that both webs are practically guided through the press between the beds and cylinders from the guide 6^e to 110 the guide 6ⁱ in exactly the same path and by the same means, so that the cylinders will present both webs to the forms simultaneously and take impressions upon both webs simultaneously. But, as the narrow web 115 w is fed more slowly than the fast web W, the forms must be differently arranged and therefore the forms from which the impressions are to be taken on the narrow web must be only half the length of the forms on which the impressions are to be taken on the wide web. This will be readily understood by reference to Figs. 4 and 5. In Fig. 4 the forms 1, 3, 5, 7, are arranged in two rows upon the bed 1 and similarly forms 2, 4, 6, 8, are 120 arranged in two rows upon the bed 2, so that 8-pages will be printed upon the wide web W, while single forms 9 and 10 are placed upon the beds 1 and 2 to be printed on the narrow web w. This arrangement will give 125 130

a 10-page paper with 5 forms on each bed. To print a 14-page paper the forms can be arranged as in Fig. 5, which shows two rows of forms on beds 1, 2, to be impressed upon the wide web giving 12 pages; while single forms 13, 14, on the beds 1, 2, will be impressed upon the narrow web.

The arrangement of forms for printing any even number of pages on one web will be obvious to pressmen and need not be described herein. When a full width web is to be printed to produce say 16 pages, the gears 4ⁱ, 4^j, can be changed so that the slow sections 4^e, 5^e, will be driven at the same speed as the sections 4^a, 5^a, and then the wide web is led through the press like web W above described, and the looping rollers 7^b, 7^m, will not be used.

If it be desired to handle a wide web through the press at slow speed, it will only be necessary to alter the gearing so as to drive both sections at the slow speed. Or if desired in order to drive sections 4^a, 5^a, at slow speed, like sections 4^e, 5^e, the sections 4^a, 5^a, can be unlocked from its shaft 4^b by withdrawing the keys 4^x, and locked to sections 4^e and 5^e in any desired manner, as for instance by a screw 4^y engaging a shoulder 4^z on section 4^e, as indicated in dotted lines in Fig. 2. Section roll 5 could be similarly constructed. This being merely a matter of mechanical selection and skill I do not wish to be restricted to any particular construction whereby the two sections of roll 4 and 5 may be driven alike, at either fast or slow speed. When the sections are driven alike at slow speed, a wide web can be led through the press-like web w and looping rollers 6^b, 6^m, will not be used. Thus I can run through this press a single wide web at slow or fast speed; or two narrow webs at different speeds.

By the means described I am enabled to print any number of pages desired up to 16 by means of a two bed and cylinder press with a very slight addition to the number of members in the ordinary 8-page duplex press, and without any material complications in the mechanism thereof.

The invention is applicable to other arrangements of beds and cylinders than that shown in the drawing and also to other than traveling-cylinder stationary-bed-presses.

Having described my invention what I claim as new and desire to secure by Letters Patent is:

1. In a printing press, the combination of a bed and co-acting cylinder, guides for directing webs between said bed and cylinder, mechanism for feeding webs to and delivering same from the press at different speeds, a looping mechanism for each web, and means for operating one looping mechanism from the other but at a different speed whereby

the webs are fed and delivered simultaneously but at different speeds.

2. In a printing press, the combination of a bed and cylinder, fast and slow feeding mechanisms for directing webs through the press, a looping mechanism for the fast web, a looping mechanism for the slow web, and mechanism whereby one looping mechanism operates the other at a different speed.

3. In a printing press, the combination of a bed and co-acting cylinder, a sectional web feeding roll having a fast and a slow portion respectively adapted to feed a web to the press, guides for directing the webs between the bed and cylinder, and mechanism for looping the fast and slow webs.

4. In a printing press, the combination of a pair of beds and co-acting cylinders, guides for directing a web or webs between said beds and cylinders, a sectional web feeding roll having a fast and a slow portion respectively adapted to feed a fast and a slow web to the press, and mechanisms for looping the fast and slow webs.

5. In a web printing press, the combination of a bed and cylinder, guides for directing a web or webs between the bed and cylinder, and means for feeding and delivering two webs through the press at different speeds; with a set of looping rollers for each web, a cam operating one set of rollers, a pivoted lever connected with the said rollers, and connections between said lever and the second set of rollers, substantially as described.

6. In a web printing press, the combination of co-acting beds and cylinders, guides for directing a web or webs between said beds and cylinders, web feeding and delivering mechanisms adapted to feed one or two webs through the press at different speeds, a frame carrying rollers adapted to loop the fast web, means for reciprocating said frame, a second frame carrying rollers adapted to loop the slow web, and a lever pivoted on the main frame and pivotally connected to both the looper frames, substantially as described.

7. The combination with web feeding and delivering devices, a plurality of sets of looping rollers, each carried in a reciprocating frame, a lever pivoted to the main frame and to each of the looping roller frames, one of the looping frames being connected to said lever intermediate the other frame and the pivot of said lever, and means for vibrating the said frames.

8. In a web printing press, the combination of co-acting beds and cylinders, guides for directing a web or webs between said beds and cylinders, web feeding and delivering mechanisms adapted to feed one or two webs through the press at different speeds, a plurality of sets of looping rollers, each car-

ried in a reciprocating frame, a lever pivoted to the main frame and to each of the looping roller frames, one of the looping frames being connected to said lever intermediate 5 the other frame and the pivot of said lever, and means for vibrating the said frames.

9. In a printing press, the combination of a bed and cylinder, guides for directing a web or webs between said bed and cylinder, 10 a sectional web-feeding roll having a fast and a slow portion, and a similar web-delivering roll, whereby two webs may be fed to and from the press at different speeds; looping devices adapted to loop the fast web, 15 looping devices adapted to loop the slow web, and connection between said looping devices whereby one is operated from the other, substantially as described.

10. In a printing press, the combination 20 of a pair of beds and cylinders, guides for

directing a web or webs between said beds and cylinders, a sectional web feeding roll having a fast and a slow portion, and a similar web delivering roll, whereby two webs may be fed to and from the press at different 25 speeds; with a pair of looping rollers adapted to loop the fast web, a pair of looping rollers adapted to loop the slow web, and connections between said sets of looping rollers whereby one set is operated from the other, 30 one set of looping rollers moving more slowly than the other, substantially as described.

In testimony that I claim the foregoing as my own, I affix my signature in presence of two witnesses.

HENRY F. BECHMAN.
